UNITED STATES PATENT OFFICE

JOHN SHARP, OF CLEVELAND, OHIO

AEROPLANE

Application filed July 20, 1927. Serial No. 207,049.

The objects of the invention are to provide an improved aeroplane having a strong compact form of body, and aerofoils, and so constructed that upwardly and forwardly directed impulses are produced by the provision of added surfaces that increase the power of suction from above and of expansion from below, also greater efficiency is obtained by increasing the extent of area of the actively functioning surfaces of the aerofoil.

By means of the improved construction also additional buoyancy is given to the machine and it is enabled to take to the air more quickly and to climb faster, and at a steeper angle with greater ease and to sustain more weight and to provide greater efficiency per square foot of supporting surface per engine horse power than when provided with planes of ordinary construction.

Further advantages acquired by the improved method of construction include a greater ease of control, an automatically acquired balance, and increased amount of working and supporting area, thus adding to the stability of the plane without enlarging its apparent size, or wing spread.

The invention includes the provision of additional inclined plane surfaces, by the construction of inclined ports or passages in the aerofoils, tail or body having their intake or suction openings located at the upper side of their surfaces, and which pass downward and rearward at an angle through the lower or supporting surfaces, and have their discharge openings in said lower surfaces.

In the improved construction the lower or outlet openings are preferably constructed wider in cross section from front to rear than the upper or intake openings. This method of construction tends to eliminate back pressure or resistance to the air flowing through the inclined passages. It also tends to increase the effective amount of suc-

tion at the upper forward intake opening, also the lower opening being the widest the passage of the streams of air across the mouth of the lower opening will be prolonged, that is will act over a longer period of time across the lower opening.

In this manner it will create a long strong, continuous action of the air on the passages and produce a greater effect than if both upper and lower openings were of the same size.

The upper and lower openings are spaced apart upon the upper and lower surfaces of the plane respectively, and the upper opening is positioned in advance of the lower opening and they are connected by rearwardly and downwardly inclined passages that pass diagonally entirely through the members of the plane in which they are installed. These members may be the aerofoils, fuselage, or horizontal stationary rudders or stabilizers, or whatever parts desired.

By means of this construction the span of the wings can be shortened since an increased amount of lifting surface is provided for a given span, and depth of aerofoil. Also a more perfect balance can be obtained which will be more easily retained, and tipping influences can be more easily overcome.

When the machine is in motion the streams of air which rush by the lower surfaces of the aerofoils will leap across the lower openings and will produce a strong draft through these passages and will create a strong suction at the upper forward ends of the passages in the direction of motion of the machine thus drawing the machine forward and upward.

Further the streams of air rushing through the passages meeting the streams of air leaping across the lower mouths of the passages will cause their expansion upward and will create a forward continuous thrust or pressure upon the plane.

In this form of construction aerofoils of greater depth than usual may be employed.

and the air rushing through the passages will give a double acting lifting effect since the air supplied from the passages will make the whole surface underneath the aerofoils more active.

In brief the following advantages are obtained by the use of passages passing downwardly through the aerofoil members and at a rearwardly inclined vertical angle.

10 The suction produced at the intake openings reduces the pressure of air above and in advance of the aerofoil by the rarefaction of the air adjacent to said openings.

This suction is caused when the machine 15 flies rapidly through the air and assists in drawing the machine upward and forward by the removal of the compressed air above the aerofoils.

Further the air discharged from the lower 20 mouths of the passages comes in contact with the lower or lifting surfaces of the aerofoil and applies an additional lifting force thereto.

Also the rearwardly directed pressure of 25 the air underneath the aerofoil as it is discharged from these passages, as it passes from contact with the under surfaces of the aerofoil, tends to break up the back drag or wash of the aerofoil on the air following the machine so as to cause the release of the passing air.

Also the under surfaces behind the passages are engaged with the air with greater lifting effect, before it loses contact or engagement with the active lifting surfaces.

In this manner the air is caused to engage with the entire under surface of the aerofoil to cause the maximum lifting effect upon every square foot thereof which will increase 40 in direct ratio with the increase of speed of the plane and with the increased amount of suction above and expansion below continuously obtained thereby.

For this reason the smallest and most compact form of machine can be made and also the greatest liner employing the improved principle of construction.

Also a tremendous momentum can be obtained with greater speed, safety and efficiency of control and the plane can travel over greater distances without refueling since a less amount of fuel will be required.

The invention is exemplified in the accompanying drawings hereinafter more fully described and specifically pointed out in the claims.

In the accompanying drawings Fig. 1 is a plan of a large monoplane, showing one row 60 of downwardly and rearwardly inclined suction passages in the aerofoils, rear stabilizers and fuselage. Fig. 2 is a front elevation thereof. Fig. 3 is a plan of the aerofoil of a large plane showing a double row of such 65 passages. Fig. 4 is a transverse section of

one of the aerofoils taken on line 1—1, on the center line of the passages.

Fig. 5 is a plan of a smaller plane showing an aerofoil having a single row of closely approximated passages separated only by 70 the transverse ribs of the aerofoil.

Fig. 6 is a similar plan showing spaced passages. Fig. 7 is a front elevation, Fig. 8 is a side elevation. Fig. 9 is a transverse section and Fig. 10 is an enlarged plan having one large inclined air passage through 75 each aerofoil.

In these views, A is the fuselage, B the wing, C the horizontal stabilizers on the sides of the rear end of the fuselage, D is the rudder and E the propeller.

Passing through the aerofoil fuselage and stabilizers are shown the suction passages F, F, having their intake openings F', F' at a higher level than thru discharge openings 85 F², F². The upper openings F', F' are advanced also to a position in advance of the lower openings F², F² thus inclining the passages downwardly and rearwardly from the intake openings above the upper surfaces of 90 the plane to the discharge openings in the lower surfaces of the plane.

These passages F may be made in any fixed members of the plane and are shown in the aerofoil, the body or fuselage and the 95 stabilizers.

The lower mouths F² of these passages F are shown to be wider from their front to their rear edges than the upper mouths F¹ thereof.

The passages extend between the longitudinal ribs F, F, of the aerofoil and may be spaced apart as shown in Figs. 6 and 10 or closely adjacent as shown in Figs. 1, 3 and 5 and thin walls may be formed of the same 105 material as the plane or of any suitable smooth surfaced material to avoid friction upon the air passing therethrough.

By the use of these inclined passages and the peculiar action they produce in general 110 on the air above and below the plane and upon the sustaining surfaces, the principle of soaring flight is employed, which will advance the art of navigation of the air to further success.

By means of this construction, compression and expansion of the air is taking place under the entire surface of the aerofoils driving the machine up and forward. At the same time that the suction action of the 120 intake openings reduces the density of the air above the machine's aerofoils, thus pulling it up and forward, due to the momentum of the machine through the air. The described action is continuously produced at 125 all times, while the machine is in motion in the air, and in this manner soaring flight is made possible.

I claim:

1. An aeroplane wing having a series of 130

angular perforations parallel and adjacent to its retreating edge, the perforations being inclined forwardly from the lower to the upper side of the wing.

5 2. An aeroplane wing, having an angular perforation through the body thereof, and parallel with the leading and retreating edges thereof, said perforation being inclined forwardly from the lower to the upper side of
10 said body and having parallel sides and edges.

In testimony whereof I affix my signature.
JOHN SHARP.
